US00D999177S

(12) **United States Design Patent** (10) **Patent No.:** **US D999,177 S**
Bennett et al. (45) **Date of Patent:** **** Sep. 19, 2023**

(54) **REMOTE CONTROLLER**

(71) Applicant: **Microsoft Corporation**, Redmond, WA (US)

(72) Inventors: **Alexander Bennett**, Seattle, WA (US); **Huaian Cheng**, Shenzhen (CN); **Jinwon Yook**, Shenzhen (CN); **Simon Cameron Dearsley**, Bellevue, WA (US)

(73) Assignee: **Microsoft Corporation**, Redmond, WA (US)

(**) Term: **15 Years**

(21) Appl. No.: **29/830,919**

(22) Filed: **Mar. 16, 2022**

(51) LOC (14) Cl. **14-03**

(52) U.S. Cl.

USPC **D14/218; D13/168**

(58) **Field of Classification Search**

USPC **D13/168; D14/218, 388**
CPC **G08C 17/02; G08C 19/00; G08C 19/12; G08C 19/28; G08C 23/04; H04B 1/202; H05B 47/10; H05B 47/19; H03J 9/00; H03J 9/02; H03J 9/04; H03J 9/06; H03J 1/0025; H01H 9/02; H01H 9/0214; H01H 9/0228; H01H 9/025; H01H 9/0235; H01H 9/0242; G06F 3/01; G06F 3/0308; G06F 3/033; G06F 3/0338; G06F 3/03543; G06F 3/038; G06F 3/14**

(57) **CLAIM**

The ornamental design for a remote controller, as shown and described.

DESCRIPTION

FIG. 1 is a front perspective view of a remote controller showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is a bottom perspective view thereof.

The broken lines depicting the remainder of the remote in FIGS. 1-9 show features that form no part of the claimed design.

1 Claim, 6 Drawing Sheets
